Attorney

UNITED STATES PATENT OFFICE

ROBERT C. SCHEMML, OF UNION CITY, INDIANA

FINISHING WELT

Application filed July 8, 1929. Serial No. 376,790.

The present invention relates to improvements in finishing welts or moulding strips made of a plurality of bead portions formed of a covering material of leather, imitation leather or other fabric, each containing a filler or core and commonly used in trimming automobile tops, bodies and the interiors thereof.

The invention relates generally to what are known to the trade as "blind nail" welts, that is, those welts which are characterized by means in the welt itself to conceal, when in operative position, the nails, tacks or other attaching means employed to secure the welt in place on the vehicle top or body to be trimmed.

It is an object of the present invention to provide a simple and inexpensive blind nail welt embodying a base formed of any suitable material and a plurality of parallel, longitudinal fillers contained in beads superposed upon the base and formed of a portion of the material which forms the base, one of which fillers is of novel formation and both of which cooperate when applied in place on a support to be trimmed to provide an efficient, attractive and durable blind nail welt.

A further object is to provide a double bead blind nail welt having in one bead a filler of a novel shape and disposition in the welt structure adapted to overlie in part and assist in holding down in place the filler contained in the other bead of the welt.

Another object is to provide a welt which is an improvement over the finishing welt disclosed in United States Letters Patent No. 1,719,729, issued to me on July 2, 1929.

Other and further objects will sufficiently appear as the description proceeds.

In the accompanying drawings, which form part of this application for Letters Patent and wherein corresponding reference characters designate the same parts in the several views:

Figure 1 is a perspective view, in section at one end, of a portion of welt embodying the present invention;

Fig. 2 is a cross sectional view of the improved welt showing the same in process of

being applied to an article of manufacture, as for example an automobile seat;

Fig. 3 is a cross sectional view showing the welt in finished applied position and illustrating to advantage the coaction of the two bead portions to conceal the fastening tacks; and

Fig. 4 is a perspective view, in section at one end showing the novel type of core or filler used in this invention.

Referring to the drawings, the reference numeral 1 thereon indicates a covering of suitable flexible fabric, such for example as leather, imitation leather or other textile material commonly employed in welt structures. This covering material is looped over upon itself along its longitudinal edges to provide oppositely disposed marginal beads, each of which encases a filler or core, designated respectively 2 and 3, and along the portion of the fabric substantially midway between the loops and on the side thereof which contacts with the beads is disposed an inner base strip 4, preferably of the same kind of material as the fabric 1. While I have shown this strip 4 as a piece separate from the bead encasing portion of the fabric 1, it is to be understood that it may be made integral therewith without departing from the spirit of my present invention.

In any event, a multi-ply welt base is provided, between the plies of which is received one edge of a pliable wire weft fabric insert 5, the opposite edge of which is inserted between the filler 2 and the bead of the encasing fabric 1 which encases said filler. The insert 5, filler 2 and the adjacent portion of the fabric 1 are preferably cemented together, and, if desired, a line of stitching 6 may be employed to secure the two contacting fabrics together underneath the filler 2.

As more particularly explained in my prior patent above identified, the wire weft insert 5 thus provides a pliable hinging member to permit the filler 2 to be lifted from the position shown in Fig. 1 to that of Fig. 2 and to hold the filler 2 in the latter position while fastening tacks or the like 7 are passed through the base portion and into the support to which the welt is to be applied. When

the filler 2 is pressed down upon the base to conceal the tacks 7, as shown in Fig. 3, the wire fabric insert 5 tends to retain the bead and its filler in this pressed down position.

It is an object of my present invention to provide a filler 3 which by its form and disposition in the welt structure will overlie the free edge of the filler 2 when the welt is in its finished, applied position, for the purpose of aiding in retaining the filler 2 in its pressed down position and of effectually preventing gapping or lifting of the filler 1 from the base portion, especially in those sections of the applied welt which must be disposed about curves. To this end I provide a filler 3 of any suitable material, such for example as moulded or extruded rubber, of a form which, as shown to advantage in Fig. 4, may be described as kidney-shaped in cross section. In other words, the filler 3 may be regarded as a single unitary core which is in effect a pair of cores, each of elliptical cross section, coalesced or merged together with their major axes forming an obtuse angle. One surface of this filler 3 is preferably in the form of a single cylindrical segment, while the opposite surface is formed of a pair of smaller cylindrical segments which meet to produce a substantially central longitudinal depression or groove 8, as best shown in Fig. 4.

The filler 3 may or may not be secured in its bead by means of cement; and the filler and its enclosing bead are attached to the base portion of the welt by a line of stitches 9, which pass in the depression or groove 8 through the bead, filler and welt base.

It will be apparent that by the construction just described the filler 3 is disposed in its bead with its outer edge held against the base of the welt, and with its inner edge raised therefrom at a slight angle to overhang a part of the base. Into the recess formed between this overhanging part of the filler 3 and the welt base is received the free edge of the filler 2, and the fillers are so proportioned that when disposed into the final finished position shown in Fig. 3 the overhanging portion of the bead which encases the filler 3 will be urged downward snugly against the bead 50 which contains the filler 2 by the line of stitching 9.

Use of a filler 3 as hereinabove explained has been found in practice to retain the filler 2 securely and firmly in its pressed down position and to successfully prevent raising of the filler 2 at all times except when a deliberate attempt is made to lift the same.

It is to be understood that while I have shown in the embodiment of the invention 100 illustrated by the drawings and described herein a filler 2 of half round formation, this filler may be provided in any suitable shape. Furthermore the filler 3 need not be of the specific shape which I have herein shown and 110 described, as long as it exhibits the essential

characteristics of a filler secured to the welt base along a line intermediate the edges of its bead and which is adapted to receive under its inner edge the free edge of a coacting other bead of the welt. Other modifications may 70 be made in the embodiment which I have chosen to exemplify the present invention, but it is to be understood that all such modifications are to be considered within the scope 75 and purview of the appended claims in so far as they embody the principle of the invention.

Having thus described my invention, what I claim and desire to secure by Letters Patent is:

1. A blind nail finishing welt comprising a covering fabric folded upon itself to form a nail receiving base portion and forming on opposite marginal edges thereof a pair of beads, one of the beads being movable to close down upon and overlie the base portion and the other bead being adapted to overlie in part a portion of the first bead when in its closed position, single unitary fillers in both beads, and stitching passing through the second bead and its filler to secure the same to the base portion.

2. A welt as claimed in claim 1 in which the filler in the second bead is provided with a longitudinal weakening groove through 95 which the stitching passes.

3. A welt as claimed in claim 1 in which the under side of the portion of the second bead which is adapted to overlie the first bead is curved upwardly from the base portion to 100 provide a recess for receiving the first bead.

4. A welt as claimed in claim 1 in which the filler in the second bead is provided on its upper surface with a longitudinal weakening groove through which the stitching passes 105 and on its lower surface with an upwardly curving portion to provide a recess between said portion and the base adapted to receive the first bead.

In testimony whereof I affix my signature. 110
ROBERT C. SCHEMML.
